RAIL JOINT COUPLING DEVICE.
APPLICATION FILED MAY 3, 1919.

Patented Dec. 16, 1919

2 SHEETS—SHEET 2.

UNITED STATES PATENT OFFICE.

LYLE M. SMITH, OF CATELLETT, VIRGINIA.

RAIL-JOINT-COUPING DEVICE.

1,325,267.

Specification of Letters Patent. Patented Dec. 16, 1919.

Application filed May 3, 1919. Serial No. 294,532.

To all whom it may concern:

Be it known that I, LYLE M. SMITH, a citizen of the United States, residing at Catlett, in the county of Fauquier and State of Virginia, have invented certain new and useful Improvements in Rail-Joint-Coupling Devices, of which the following is a specification, reference being had therein to the accompanying drawings.

10 This invention relates to rail joint coupling devices, and has for its object the construction of a simple and efficient device for fastening the contiguous ends of a pair of rails together.

15 Another object of the invention is the improvement of the construction of the angle plates and the wedge keys, whereby an efficient joint after fastening the contiguous ends of the rails together will be produced.

20 With these and other objects in view, my invention comprises certain novel constructions, combinations, and arrangements of parts as will be hereinafter specifically described, illustrated in the accompanying

25 drawings, and more particularly pointed out in the appended claims.

In the drawings,

Figure 1 is a top plan view of a device constructed in accordance with the present invention, while

Fig. 2 is a view in side elevation of the device illustrated in Fig. 1.

Fig. 3 is a section taken on line 3—3, Fig. 2, looking in the direction of the arrows.

Fig. 4 is a perspective view of the bridge or base plate.

Fig. 5 is a perspective view of the wedge plate.

Fig. 6 is a sectional view taken on line 6—6, Fig. 2, looking in the direction of the arrows.

Fig. 7 is a perspective view of the primary wedge key, while

Fig. 8 is a front edge view of said key.

Fig. 9 is a fragmentary sectional view of my device, showing particularly the V-shaped lugs and the V-shaped notches or pockets formed on the abutting ends of the

50 rails.

Referring to the drawings by numerals, 1 designates contiguous ties, and 2 is the bridge or base plate resting upon the ties.

The rails 3 rest upon the base plate 2, and 55 by means of spikes 4 extending through apertures 5 of the plate 2, and into the ties

1, the rails are held in position upon the base plate.

The joint device includes a pair of similarly-constructed angle plates 6 molded or integral with the base plates 2; each angle plate is provided with a beveled edge 7 that is formed in a different vertical plane from the main edge 8, for the purpose hereinafter described.

60 The base plate 2 is provided with a pair of transverse grooves 9; each groove 9 tapers or increases in height from end 10 to end 11, to accommodate the tapering wedge plate 12.

65 The wedge plate 12 is provided with a head 13, having a beveled edge 14, which beveled edge 14 engages the beveled edge 7 of an angle plate 6, so that as the wedge plate 12 is drawn more tightly upon the base plates 2, the abutting faces or edges 14 and 75 7 of the wedge plate 12 and the angle plate 6, respectively, act to force the angle plate more tightly against the base of the rail 3 (Fig. 3). The wedge plate 12 is tapered from one end to its opposite end, and formed 80 in said plate near its outer end is an elongated, key-receiving slot 15.

After the two base plates 2 have been placed upon the ties 1, then the rails 3 are placed upon the base plates between the angle plates 6 (Figs. 1, 2, and 3), and then the wedge plates 12 are pushed through the grooves 9,

causing the elongated slots 15 to be exposed at the outer side of one of the base plates 2, which slots 15 receive the primary wedge 90 keys 16.

Each primary wedge key 16 comprises a body 17, split or bifurcated longitudinally at 18, and through the split or bifurcated portion of the body 17 is formed an elongated slot 19 for receiving the auxiliary wedge key 20; it is to be noted that the slot 19 is formed at right angles to the slit portion 18, thereby permitting the lower split end of the primary wedge key to be bent outwardly, as shown by dotted lines 21 100

(Fig. 2). After the auxiliary wedge key has been placed in the slot 19 of the primary key, then the auxiliary, split, wedge key 20 can be spread apart at its split end to lock this key securely upon the primary 105 key (Fig. 1); the auxiliary key 20 has a

beveled edge 22 so that it can be tightly jammed or wedged into the slot 19 of the primary key, after which the split end can be spread apart as shown in dotted lines in 110 Fig. 1.

The body 17 of each primary wedge key

- 16 has its inner edge 23 beveled, and the inner edge 24 of the head 17^a is more radically beveled than at 23, whereby, when the key 16 is being forced downward in aperture 15 of wedge plate 12, the key 16 will serve to draw the wedge plate more tightly upon the two base plates 2 and their integral angle plates 6, by reason of the edge 25 of one of the base plates 2 being slightly beveled, and as pressure is continued upon the head 17^a, the radically-beveled edge 24 of the head 17^a will come in contact with the beveled edge 7 of an angle plate, opposite to the head 13 of the wedge plate (Fig. 3), causing a greater pressure to be exerted for clamping the angle plates tightly against the web of the rails and under the tread of the rails, producing a very efficient assembling of the contiguous ends of the rails, whereupon the auxiliary wedge keys 20 are inserted in slots 19 of the primary wedge keys, and all of the elements of the device are thereupon fastened securely and efficiently in their tightly-assembled position.
- 25 To prevent the rails 3 from "creeping," I form on the inner face of each angle plate 6, contiguous to the base plate 2 (Fig. 4), an integral V-shaped lug 25^a, and these lugs 25^a of the angle plates fit into V-shaped sockets 26 (Fig. 9); these sockets are formed by beveling at 27, for a short distance, the abutting ends of the rails 3. When the base plates 2 and the angle plates 6 are brought against the contiguous or abutting ends of the rails 3, the lugs 25^a will be seated in the sockets 26, and thereby prevent any longitudinal play or creeping of the rails upon the coupling device.
- I appreciate that certain minor changes or alterations may be made in the extensive manufacture of my device, and I reserve the right to make such minor alterations or changes as shall appear to one skilled in the art to which this invention relates, and which shall fairly fall within the scope of the appended claims.
- What I claim is:
1. In a device of the class described, the combination of base plates provided with a pair of transverse, tapering, or wedge-like grooves, rails resting upon said base plates, angle plates integral with said base plates and bearing against the contiguous ends of said rails, each angle plate provided at its lower edge with a beveled face formed in a different plane from the plane in which the remaining portion of the face of the plate is formed, a tapering, wedge plate provided at one end with a head having an inner, beveled edge and having near its opposite end an elongated slot, the beveled, inner edge of each wedge plate engaging the lower, beveled face of one of said angle plates, one of said base plates provided with a beveled edge, an elongated slot of each wedge plate contiguous to the beveled, lower face of one of the angle plates and contiguous to the beveled edge of one of the base plates, a primary wedge key in the slot of said wedge plate, each key having a body with an inner, beveled edge and a head with an inner, beveled edge, the beveled edge of the body normally resting against the beveled edge of said base plate and the beveled edge of the head normally resting against the beveled face of an angle plate, said body of the key provided with a slot, and an auxiliary wedge key in the slot of the first-mentioned key.
  2. In a device of the class described, the combination with base plates, rails upon said base plates, of angle plates integral with said base plates and engaging the contiguous ends of said rails, wedge plates under said rails and resting upon said base plates, each wedge plate provided with a head at one end engaging an angle plate and provided near its opposite end with an elongated slot, primary wedge keys in the slots of said wedge plates, each key provided with an elongated slot, an auxiliary wedge key in the slot of each primary key, and the outer end of each of the primary and auxiliary keys being bent at an angle to the body of the key, when assembled.
  3. In a device of the class described, the combination with base plates, rails resting upon said base plates, of angle plates integral with said base plates engaging contiguous ends of said rails, wedge plates extending under said angle plates and said rails and upon said base plates, each angle plate provided with an elongated slot contiguous to the lower edge thereof and the upper edge of a base plate, said lower edge of the angle plate and the edge of the base plate contiguous to said slot being both beveled in the same vertical plane, and a wedge key having a beveled inner edge in said slot of the wedge plate and one of the inner, beveled edges of the wedge key engaging the beveled edge of the base plate and the other beveled edge of the key engaging the beveled edge or face of the angle plate, substantially as shown and described.
  4. In a device of the class described, the combination with base plates, rails resting upon said base plates, angle plates integral with said base plates, and engaging said rails, of wedge plates extending under said rails and said angle plates and resting upon said base plates, primary wedge keys extending through said wedge plates and bearing against one of the angle plates and one edge of one of the base plates, and auxiliary wedge keys extending through the primary wedge keys and serving to hold all of the parts together in a locked position.
  5. In a device of the class described, the combination with base plates, rails resting

upon said base plates, angle plates integral with said base plates and engaging the contiguous ends of said rails, of wedge plates extending under said angle plates and resting upon said base plates, primary bifurcated and slotted wedge keys extending through the wedge plates and engaging one of said angle plates and one of said base plates, and auxiliary bifurcated wedge keys

extending through the slotted portions of 10 said primary keys, the bifurcated ends of said primary and auxiliary keys spread apart when assembled, for securely locking the same together.

In testimony whereof I hereunto affix my 15 signature.

LYLE M. SMITH.
